United States Patent Office

Des. 189,505
Patented Dec. 27, 1960

189,505

SPECTACLE FRAME

Harold A. Lambert, Plainville, Mass., assignor to Universal Optical Company, Inc., Providence, R.I., a corporation of Rhode Island

Filed July 26, 1960, Ser. No. 61,518

Term of patent 14 years

(Cl. D57—1)

Fig. 1.

Fig. 2.

Fig. 1 is a front elevational view of a spectacle frame embodying my new design; and

Fig. 2 is a side elevational view thereof.

The dominant features of my design reside in the portions shown in full lines.

I claim:

The ornamental design for a spectacle frame, substantially as shown and described.
